CROSSING SIGNAL

Mercer D. Wilson, Phoenix, Ariz.

Application March 18, 1935, Serial No. 11,597

13 Claims. (Cl. 246—130)

This invention relates to traffic control devices, particularly to automatic signal mechanisms for railroad crossings, and is directed to an improvement of the device shown in my Patent Number 1,890,352, issued December 6, 1932, entitled "Crossing signals".

The present invention embodies the same general principles as those disclosed in the aforesaid patent. A signal means adapted to control traffic across a railroad track reciprocates between a "Stop" position and a "Go" or clear position, one movement of the reciprocation being effected by power-driven mechanism, and the opposite movement being accomplished by the force of gravity. By this arrangement, the power-driven movement not only moves the signal member from one position to another, but also, by displacing a suitable weight against the force of gravity, stores energy in the form of energy of position to be used in accomplishing the second and opposite movement of the signal member. Preferably, the signal member indicates "Go" when it is at the end of the power-driven movement, energy then being stored for the opposite movement of the signal member to the "Stop" position. In other words, when the signal is in the clear position, potential energy is available for the second movement, and an approaching train or control vehicle merely releases the stored energy. After the departure of the train, the reverse power-driven movement is automatically initiated and then completed to place the parts in their "Go" position. The word normal as hereinafter used will refer to the position of the mechanism at the "Go" or clear position of the signal.

An important advantage of this arrangement is that if the power-driven mechanism fails, the signal member will subsequently fail to move from the "Stop" position when the train clears the controlled zone, thereby calling attention to the condition of the mechanism before any serious accident can be caused by the break-down.

An additional safety feature is that the signal is maintained in the "Go" position only so long as an electric control circuit is energized. Consequently, whenever the control circuit fails or is broken by accident or for some other reason, the signal member will immediately move to the "Stop" position, regardless of the proximity of a train, thereby calling attention to the need for immediate repair.

As in my previous disclosure, I prefer that the power-driven mechanism comprise an hydraulic lift actuated by an electrically driven pump.

One object of my improvement is to provide for maintaining the signal in the "Go" position by a positive latch instead of by fluid pressure, and to further provide for opening the latch in a positive manner by utilizing the impact of an auxiliary weight released when the train enters the control zone. Another object of my invention is to provide for controlled non-uniform movement of the signal member from the "Go" position to the "Stop" position. The signal is arranged to move suddenly to an intermediate warning position and then to proceed slowly to the "Stop" position, the latter movement being subject to precise adjustment.

The above and other objects and advantages of my improvement will be apparent from the detailed description to follow, considered with the accompanying drawings, in which—

Fig. 1 is a side elevation of my invention;

Fig. 2 is an enlarged side elevation with the outer housing or casing shown in section;

Fig. 3 is a vertical, medial section of Fig. 2 on a somewhat larger scale;

Fig. 4 is a plan view of the mechanism within the signal housing, taken with the signal in the "Stop" position;

Fig. 5 is similar to Fig. 4, with the signal in the "Go" position;

Fig. 6 is an elevation of the mechanism in the upper part of the housing, with the signal in the "Stop" position;

Fig. 7 is similar to Fig. 6, with the signal in the "Go" position;

Fig. 8 is a horizontal section of the signal mechanism, taken as indicated by the line 8—8 of Fig. 7;

Fig. 9 is a vertical section, taken as indicated by line 9—9 of Fig. 8;

Fig. 10 is a vertical section, taken as indicated by line 10—10 of Fig. 9, with the signal mechanism in the "Stop" position;

Fig. 11 is similar to Fig. 10, with the signal mechanism at the end of the movement to the "Go" position;

Fig. 12 is a vertical section as indicated by the line 12—12 of Fig. 8, with the signal in the "Stop" position;

Fig. 13 is similar to Fig. 12, showing the movable parts at the end of the movement to the "Go" position;

Fig. 14 is a wiring diagram, indicating one electrical arrangement that may be embodied in the invention; and

Fig. 15 is a wiring diagram showing a second electrical arrangement that may be employed.

The mechanism of the signal is housed in a cylindrical casing 20 having a conical top 21. The base plate 22 of the casing is integral with a platform 23 that supports the major part of the mechanism.

My invention is not limited to any particular type of signal member, nor any particular elevation of the signal member above the ground. It is an object of the preferred form of my invention, however, to provide a lower signal member in the form of a barrier, generally designated by numeral 24, mounted to yield to the impact of a vehicle, and an upper signal member, generally designated by numeral 25, independent of the barrier and of sufficient elevation to clear vehicles. The manner in which the requisite degree of independence of these two signal members may be attained will become apparent with further description.

20 The upper signal member 25 includes a horizontally extending arm 26 rigidly mounted to vertical signal shaft 27 by means of a suitable T fitting 28, the arm being suitably braced by a cable 26a extending to a top fitting 29 on the vertical signal shaft. The barrier, or lower signal member, 24 is mounted on a horizontal arm 30 extending from a sleeve 31 that rotatably embraces the signal shaft. Preferably, barrier 24 is counterbalanced by a suitable weight 32 on a 25 diametrically opposite arm 33 also mounted on sleeve 31, a suitable cable 34 bracing the barrier and two similar cables 35 and 36 bracing arm 33.

To protect the upper end of sleeve 31 from moisture, an overhanging conical protector 37 may be suitably positioned on signal shaft 27; and for further protection from the weather, a conical shield 38, having a vertical skirt 39, may be connected to sleeve 31 in a position to cover the top of the signal casing, as shown.

40 Signal sleeve 31 is operatively associated with a signal drive shaft 40 through a flexible connection that will permit, under certain circumstances, a degree of independent movement. The purpose here is to avoid damage to the mechanism by a vehicle colliding with barrier 24. Such a flexible connection may comprise a suitable yoke 41 embracing and supporting sleeve 31, together with a complementary revolvable signal base 42 suitably mounted on the upper end of drive shaft 40 as by screw-threaded engagement. Yoke 41 has two diametrically positioned arms 43 that turn downward and terminate in suitable non-friction members, such as revolvably mounted balls 44 that ride on signal base 42. Yoke 41 45 floats on signal base 42 and is kept centered with respect to the signal base by virtue of the fact that the lower end of signal shaft 27 is embraced by the signal base. A suitable key 45 causes signal shaft 27 to turn with signal base 42.

60 Signal base 42 has a radial flange 46, at the periphery of which a vertically disposed annular flange 47 serves as a circular track for balls 44 of yoke 41. At diametrically opposite points, annular flange 47 rises to apexes 48 and at 90 degrees from the apexes the annular flange falls to diametrically opposite low points or valleys 49. It is apparent that normally yoke 41 will ride in valleys 49, barrier 24 turning in vertical alignment with upper signal member 25, and that 70 should a vehicle collide with barrier 24, displacing it from its usual alignment with member 25, a cam action will be provided to return the barrier to such alignment.

The lower end of signal drive shaft 40 is 75 revolvably supported by a suitable thrust bearing

50 mounted in top casting 51 of the main hydraulic cylinder 52. The upper end of the signal drive shaft is kept in vertical alignment by a suitable annular bearing 53 embracing the lower portion of signal base 42. This upper bearing 5 is mounted on a horizontal plate 54 that is supported largely by casing 20. Either or both of these bearings may support the major portion of drive shaft 40 and the associated elements here- 10 to described.

Drive shaft 40 is actuated by movement of a suitable weight 55, the operative connection between the two being such that vertical movement of weight 55 from the position shown in Fig. 6 to that shown in Fig. 7 causes shaft 40 to 15 rotate approximately 90 degrees in one direction, and the reverse movement of weight 55 causes the reverse rotation of the shaft. Preferably, this operative connection is provided by means of spiral ribs 56 associated with weight 55 in mesh 20 with complementary spiral grooves 57 on the periphery of drive shaft 40. The ribs may be formed in a hard Babbitt liner 58 of a nickelized steel sleeve 59 incorporated in weight 55. Weight 55 may be held against axial rotation by suitable guide rods 60 that are slidably embraced by bronze bushings 61 incorporated in the body of the weight.

The mass of weight 55 is such that by force of gravity alone it will move freely, if unsupported, from its normal position at the upper end of its range of movement to its lowermost position, thereby revolving shaft 40 to place the two signal members in the "Stop" position.

The power means for moving weight 55 upward 35 preferably includes a hydraulic lift. In the construction shown, hydraulic cylinder 52, mounted on platform 23, encloses a suitable piston 62 from which two spaced piston rods 63 extend upward, terminating in weight 55.

To limit the upward movement of the piston under hydraulic action, it may be provided with a suitable relief valve 64 that normally covers relief passages 65. The valve includes a stem 66 extending upward a suitable distance towards 45 top casting 51. The valve is normally maintained in a closed position by virtue of a suitable helical spring 67 confined between piston 62 and a stop 68 on the stem.

It may be noted here that in the construction 50 shown the piston reciprocates only over the lower portion of cylinder 52. The pump, generally designated by numeral 69, is mounted below the cylinder in the space between platform 23 and base plate 22. The pump may be of the gear type, 55 comprising two interlocking rotary elements 70 and 71 in pump chamber 72. The two rotary elements are mounted, respectively, on shafts 73 and 74, shaft 74 being driven by a suitable motor 75.

Any fluid may be used in the hydraulic lift, preferably a suitable grade of oil. The space in cylinder 52 above the piston is utilized as a reservoir, the oil being pumped out of the reservoir into the cylinder under the piston to raise the 65 weight, and the oil being returned to the reservoir when the weight is permitted to force the piston downward. The drawings show an arrangement that may be employed to provide such a cycle of fluid movements.

From a port 76 in the cylinder wall just above the upper position of piston 62 (Figs. 12 and 13), a down-flow passage 77 (Fig. 10) leads to pump chamber 72. From the outlet side of the pump a pressure passage 80 leads to the bottom of a ver- 70 75

tically disposed valve chamber 81, in which a valve 82 is free to move longitudinally from a normal lower position, shown in Fig. 10, to an alternate higher position, shown in Fig. 11, the valve 5 moving upward by fluid pressure from the pump. The valve includes an extensive stem 83 terminating in a valve head 84. Preferably, the gravitational return of the valve is facilitated by a helical spring 85 confined between valve head 84 and the upper end wall 86 of the valve chamber. End wall 86 has a suitable bleeder port 87 to provide ready escape of any fluid trapped above the 10 valve head.

When the valve is in its uppermost position, it 15 clears a lower valve port 88 from which a passage 89 leads to a port 90 in the cylinder wall below the lowermost position of piston 62. In such position of the valve an upper valve port 91 is cut off from both pump pressure passage 80 and the 20 lower cylinder passage 89. In the lowermost position of the valve (Fig. 10), pressure passage 80 is cut off and communication is established between the space in the cylinder under piston 62 and the space in the cylinder above piston 62 as follows: 25 port 90, lower cylinder passage 89, port 88, valve chamber 81, upper valve port 91, up-flow passage 92, and spaced ports 93 and 94 in the cylinder wall above the uppermost position of the piston. It will be noted that the arrangement is equivalent to an ordinary three-way valve responsive 30 to fluid pressure, i. e., when the pump is in operation fluid pressure forces the valve to its uppermost position, thereby placing the pump in communication with the cylinder under the piston, and, when the pump ceases operation, the valve 35 automatically returns to a position placing the lowermost portion of the cylinder in communication with the uppermost portion of the cylinder.

Since oil trapped in pump pressure passage 80 40 may hinder, if not prevent, the downward return of valve member 82, either the pump must permit sufficient reverse leakage to release the trapped oil or a suitably dimensioned bleeder passage 95 must be provided between pressure passage 80 and down-flow passage 77.

Normally, the weight is held at its uppermost position independent of the hydraulic lift by virtue of a lock means that will be described later. When a train or control vehicle enters the control 50 zone of the track, the weight is released to gravitate downward, thereby turning the signal to the stop position and forcing oil from the bottom of the cylinder to the top of the cylinder through passage 92. One of the objects of this invention 55 is to provide relatively fast movement of the signal for the first 30 degrees and relatively slow movement for the remaining 60 degrees. This object may be accomplished by controlling the flow of fluid through passage 92 in accordance with the desired rate of movement of the signal.

For this purpose, the upper portion of passage 60 92 is enlarged to a time-control cylinder 96 in which reciprocates a time-control plunger 97. By means of a connecting rod 98 extending upward through a suitable packing gland 99, time-control plunger 97 is connected to a bracket 100 integral with weight 55 (Fig. 7). Plunger 97 has one or more longitudinal passages 101 dimensioned to 65 suitably restrain the flow of oil through up-flow passage 92. Preferably, adjustment of degree of restraint of oil flow is provided by a suitably apertured complementary disk 102 having apertures corresponding to passages 101 in the time-control 70 plunger. This disk may be held fixed by nut 103

at any of various positions partially closing passages 101.

The reasons for providing two ports 93 and 94 spaced as shown will now be apparent. In the normal position of the signal, time-control 5 plunger 97 clears lowermost port 93 by a distance corresponding to the first 30 degrees of the signal movement. When the weight is released to gravitate downward, the time-control plunger will not restrict the flow of fluid through passage 92 until 10 it begins to cut off ports 93. Thereafter, however, the downward movement of the weight will be retarded by the restricted flow of the oil through apertures 101 until the time-control piston reaches its lowermost position, indicated in 15 Fig. 10. Two spaced ports are required so that when the time-control plunger is passing over lowermost port 93, uppermost port 94 is available for oil passage.

The latch means to releasably retain the weight 20 at its normal uppermost position independent of the hydraulic lift may be associated either with the weight itself or with drive shaft 40. In the arrangement shown, the latch is associated with the shaft through signal base 42. 25

A suitable latch pinion 104 (Figs. 4-7), mounted on the periphery of signal base 42 in radial alignment to the axis of shaft 40, meshes with an arcuate rack 105 mounted on plate 54. A pawl 106 overhanging the normal position of pinion 104 30 is pivotally mounted in a suitable latch bracket 107, the bracket being mounted on plate 54.

Mounted in bracket 107 on the same axis as pawl 106 is a latch rocker arm 108. The inner end of this rocker arm is provided with an arcuate 35 slot 109 which confines a pin 110 extending laterally from pawl 106. This inner end of the rocker arm is operatively connected by a downwardly extending portion 108a to a suitable motor cut-off switch 111 mounted on plate 54, 40 which switch may be of the mercury type adapted to rock between open and closed positions. When the inner end of the rocker arm is down, i. e., in the normal position shown in Fig. 7, switch 111 is open; and when the rocker arm is in the alternate 45 position of Fig. 6, the motor cut-off switch is closed. It will be noted that when the inner end of the rocker arm is down, slot 109 permits 50 pivotal movement of the latch in a range of engagement with pinion 104, but when the inner end of the rocker arm is at its uppermost position (Fig. 6) the pawl is lifted clear of the pinion.

From the outer forked end of rocker arm 108 pivotally depends a stirrup 112 that passes through a vertical slot 113 in a latch weight 114. An armature 115, integral with the upper end of weight 114, is designed to co-operate with a U-shaped electro-magnet 116. Electro-magnet 116 has a suitable coil 116a and is mounted on a horizontal extension 118 of bracket 107, the electro-magnet being within the fork of rocker arm 108. 60

In the normal position of the various parts of the latch mechanism shown in Fig. 7, the latch weight is held at its uppermost position by virtue of electro-magnetic coupling between armature 65 115 and electro-magnet 116, and rocker arm 108 is held in a position with the inner end depressed by virtue of the fact that stirrup 112 is held up by the bottom of slot 113.

When the electro-magnet 116 is de-energized 70 by a train entering the control zone of the track, latch weight 114 is released to gravitate downward. Slot 113 is of sufficient length to provide a substantial degree of lost motion between latch weight 114 and stirrup 112, so that the re- 75

leased weight strikes the stirrup with sufficient force to draw the forked end of rocker arm 108 downward in a positive manner. As long as a train is in the control zone, weight 114 will remain suspended from stirrup 112 in the position shown in Fig. 6, the downward movement of the weight being limited by the operative connection between rocker arm 108 and switch 111.

While electro-magnet 116 is of sufficient strength to hold the weight suspended in the position shown in Fig. 7, it is not of sufficient strength to draw the weight upward against gravity from the position shown in Fig. 6. I have, therefore, provided automatic means for restoring the latch weight to its normal position upon the arrival of signal weight 55 at its uppermost position.

Below the weight, a vertically disposed cut-off cylinder 119 communicates with main cylinder 52 by an upper passage 120 and a lower passage 121, lower passage 121 opening thence to a chamber 122 on the wall of the main cylinder 52. Towards the upper end of chamber 122 a bore or group of bores generally designated by numeral 123 extends through the wall of cylinder 52, and a similar bore or group of bores, generally designated by numeral 124, extends through the wall of the main cylinder near the lower end of chamber 122. A suitable cut-off plunger 125 slidably mounted in cut-off cylinder 119 is mounted on a rod 126. The rod extends upward through a packing gland 127 into a vertical bore 128 in weight 114. A suitable helical spring 129 embraces rod 126 below weight 114, the spring resting upon a suitable sleeve 130 adjustably mounted on the rod.

Normally, i. e., when the signal is in the clear position and no train is in the control zone of the track, rod 126 rests upon the bottom end plate 131, holding cut-off plunger 125 at a position just above passage 121, and no effective pressure is exerted by spring 129 against the bottom of latch weight 114. The normal positions of these elements are shown in Figs. 7 and 12.

When latch weight 114 is released by a train entering the control zone, it may fall far enough to partially contract spring 129, as shown in Fig. 6. As soon as the train clears the control zone, motor 75 is energized and pump 69 begins to deliver oil to the bottom of cylinder 52 beneath piston 62. When piston 62, on its upward movement, opens the lowermost of bores 124, oil under pressure escapes into chamber 122 and passage 121 to exert pressure on the under side of cut-off plunger 125. The full force of the oil pump is not delivered against the cut-off plunger initially, however, because bores 123 and bores 124 are so spaced that momentarily oil flows both outward from underneath the piston through one or more bores 124 and inward above the piston through one or more bores 123. This momentary condition ceases as piston 62 moves upward to completely cover bores 123 and completely uncover all of bores 124, so that the full force of the pump is thereafter delivered against cut-off plunger 125.

The cut-off plunger is forced upward, carrying with it rod 126, the upward movement forcing weight 114 into the normal position shown in Fig. 7. It will be noted that spring 129 serves as a shock-absorber and permits a certain latitude in the adjustment of sleeve 130. If, for any reason, motor cut-off switch 111 is not closed by the arrangement described to stop the pump, damage to the mechanism will be prevented by

the action of relief valve 64, as previously described.

As soon as pump 69 stops, cut-off plunger 125 returns to its normal position at the lower end of its range of reciprocation and latch weight 114, except for the attraction of electromagnet 116, is again free to drop down upon stirrup 112. It is contemplated that all pressure in cylinder 52 beneath the piston will be released immediately after the pump stops by virtue of valve 82 returning to its lowermost position and thereby providing free communication from port 90 at the bottom of the cylinder to ports 93 and 94 at the top of the cylinder.

In my previously granted patent, referred to above, I disclose a wiring diagram, the principles of which may be adapted to the present device. The essence of such an arrangement consists in providing two control switches, both of which must be closed to energize the signal motor, one being a mechanically operated switch that opens only when the signal is in the "Go" position, the other being an electrically operated switch open only when a train is in the control zone. Both switches, in such an arrangement, will be closed to operate the motor whenever the signal is in the "Stop" position and no train is in the control zone.

A simple form of such a wiring diagram is shown in Fig. 14. Relay 132 is normally energized in the closed position by wires 133 and 134 that are part of a circuit associated with the control zone of the railroad track. Whenever a train enters the control zone this circuit is short-circuited to de-energize relay 132, thereby breaking the normal circuit through electromagnet 116. This last named normal circuit includes wire 135, battery 136, wire 137, relay member 138, and wire 139 to the other side of the electromagnet.

When the electro-magnet releases weight 140 of the wiring diagram, which represents latch weight 114 in the device itself, a switch member 140a connects contacts 141 and 142, the switch member and two contacts representing cut-off switch 111. As long as the train is in the control zone, relay 138 remains open and switch member 140a bridges contacts 141 and 142. As soon as the train leaves the control zone, the signal being in the "Stop" position, relay 132 closes to re-establish the normal circuit through electro-magnet 116 and also the following circuit through motor 75: battery 136, wire 135, wire 143, motor 75, wire 144, switch member 140a, wire 145, wire 139, relay member 138 and wire 137 back to battery 136.

The wiring diagram of Fig. 15 is similar to Fig. 14, but provides for controlling the motor through a motor relay 146. Corresponding parts of the two wiring diagrams are given corresponding numbers. Normally, electro-magnet 116 is energized by the circuit above described and since switch member 140a is spaced from contacts 141 and 142, relay 146 is de-energized.

When a train enters the control zone, relay 132 opens, thereby de-energizing electro-magnet 116. When switch member 140a drops to bridge contacts 141 and 142, relay 146 does not close because the relay circuit includes relay member 138. When, however, the train leaves the control zone and relay 132 closes, motor relay 146 is energized through the following circuit: battery 136, wire 137, relay member 138, wire 139, wire 145, switch member 140a, wire 147, coil of relay 146, wire 148, and wire 135 back to battery 136. When relay 146 is thereby energized, the follow-

ing motor circuit is established: battery 136, wire 137, wire 149, relay member 150, wire 151, motor 75, wire 143 and wire 135 back to battery 136.

The operation of my invention may be readily understood from the foregoing description. When the various moving parts are in their normal positions with the control zone of the track clear, track relay 132 is closed; electro-magnet 116 is energized; cut-off switch 111 is open; the signal is in the "Go" position; weight 55 and piston 62 are at their uppermost positions by virtue of the latch mechanism; latch weight 114 is held at its highest position by electro-magnet 116; cut-off plunger 125 rests at its lowermost position; and since the motor and pump are idle, valve 82 is at its lowermost position, providing free communication between the portion of the cylinder below the piston and the portion of the cylinder above the piston.

As soon as a train enters the control zone, thereby de-energizing the track relay, electro-magnet 116 is de-energized, releasing latch weight 114. The latch weight drops with considerable impact against stirrup 112, thereby disengaging the latch with a jerk, and at the same time closing motor cut-off switch 111. The latch is held suspended in the position shown in Fig. 6. Pinion 104, being free to rotate, moves around rack 105 as signal base 42 and shaft 40 are rotated by the downward movement of weight 55. The signal swings rapidly 30 degrees until time-control plunger 97 becomes effective, and then proceeds more slowly the remaining 60 degrees to the "Stop" position.

As soon as the control zone of the track is again clear, the motor circuit is re-established, as heretofore described, and pump 69 begins to deliver oil through the cylinder under piston 62, valve 82 being moved to its upper position automatically. The pump continues to force piston 62 and weight 55 upward until oil escaping from the cylinder through bores 124 forces cut-off plunger 125 upward to close cut-off switch 111 and to permit pawl 106 to drop into engagement with pinion 104.

If the track circuit fails for any reason, relay 132 will open, thereby de-energizing electro-magnet 116 to cause the signal to turn to the "Stop" position. If the motor circuit should fail, the track circuit remaining operative, the signal will remain in the "Go" position until a train in the control zone causes the weight to be released to turn the signal to the "Stop" position; and then upon re-energization of the track relay, the signal will remain in the "Stop" position, thereby inviting attention to the motor circuit. It is apparent that by providing gravitational movement of the signal from the "Go" to the "Stop" position, I have avoided many of the hazards ordinarily inherent in an electrically operated signal.

I have described a preferred form of my invention in specific detail for the purpose of disclosing and illustrating the principles involved. Since this preferred form suggests a wide range of modifications that come within the spirit of my invention, I reserve the right to all such modifications that are properly within the purview of my appended claims.

Having described my invention, I claim:

1. In a signal mechanism adapted to gravitate from one signal position to another, the combination of: a latch to releasably hold the signal mechanism against gravitation; a latch weight; an electro-magnet adapted to hold the latch

weight elevated, said weight being adapted to open the latch by impact when released by the electro-magnet; and an electric circuit normally energizing said electro-magnet, said circuit being adapted to be interrupted by an approaching control vehicle to release the latch weight.

2. A signal having, in combination: a signal member movable between two positions; a signal weight movable from a lower position to an upper position and vice versa, said signal weight being operatively connected to the signal member whereby the upward movement of the signal weight will move the signal to one position and the reverse gravitation of the signal weight will move the signal to the alternate position; a latch to releasably hold the signal weight against gravitation; a latch weight; an electro-magnet adapted to hold the latch weight elevated, said weight being adapted to open the latch by impact when released by the electro-magnet; an electric circuit normally energizing said electro-magnet, said circuit being adapted to be interrupted by an approaching control vehicle to release the latch weight; and power means adapted to be energized upon departure of the control vehicle to lift the signal weight to its normal latched position and to lift the latch weight to the electro-magnet.

3. A signal having, in combination: a signal member movable between two positions; a signal weight movable from a lower position to an upper position and vice versa, said signal weight being operatively connected to the signal member whereby the upward movement of the signal weight will move the signal to one position and the reverse gravitation of the signal weight will move the signal to the alternate position; a latch to releasably hold the signal weight against gravitation; a latch weight; an electro-magnet adapted to hold the latch weight elevated, said weight being adapted to open the latch by impact when released by the electro-magnet; an electric circuit normally energizing said electro-magnet, said circuit being adapted to be interrupted by an approaching control vehicle to release the latch weight; electrically actuated means to lift the signal weight and the latch weight back to their elevated positions; a second electric circuit to energize said electrically actuated means; and two switches controlling said second circuit, the circuit being energized only when both switches are closed, one of said switches being normally closed and being adapted to open temporarily in response to the approaching control vehicle, the other switch being adapted to open automatically when the signal weight reaches its normal latched position and to close when the signal weight drops from said normal position.

4. A signal having, in combination: a signal member movable from a "Go" to a "Stop" position and vice versa; a signal weight movable from a lower position to an upper position and vice versa, said signal weight being operatively connected to the signal member whereby the upward movement of the weight will move the signal member to the "Go" position and the reverse gravitation of the signal weight will move the signal member to the "Stop" position; means to lift the signal weight against gravity; means to retain the signal weight at its higher position, said retaining means being adapted to release the signal weight in response to the approach of a control vehicle; a fluid chamber having an outlet passage; means operated by the falling weight

5. to expel fluid from the chamber through said outlet passage; and a time control means adapted to be moved by the falling weight against the fluid stream in said outlet passage, said control means 10 restricting flow through said passage, thereby retarding the fall of the plunger.

5. A signal having, in combination: a signal member movable in one direction from a "Go" position to an intermediate warning position and 10 then to a "Stop" position and in the opposite direction from the "Stop" position back to the "Go" position; a signal weight movable from a lower position to an upper position and vice versa, said signal weight being operatively connected 15 to the signal member whereby the upward movement of the weight will move the signal member to the "Go" position and the reverse gravitation of the weight will move the signal member first to the warning position and then to the "Stop" 20 position; means to lift the signal weight against gravity; means to retain the signal weight at its higher position, said retaining means being adapted to release the weight in response to the approach of a control vehicle; and means to 25 retard the fall of the weight between the warning position and the "Stop" position.

6. A signal having, in combination: a signal member movable in one direction from a "Go" position to an intermediate warning position and 30 then to a "Stop" position, and in the opposite direction from the "Stop" position back to the "Go" position; a signal weight movable from a lower position to an upper position and vice versa, said signal weight being operatively connected 35 to the signal member whereby the upward movement of the weight will move the signal member to the "Go" position, and the reverse gravitation of the weight will move the signal member to the warning position and then to the 40 "Stop" position; means to lift the signal weight against gravity; means to retain the signal weight at its higher position, said retaining means being adapted to release the weight in response to the approach of a control vehicle; a fluid chamber 45 having an outlet passage; means operated by the falling weight to expel fluid from the chamber through said outlet passage; and means operated by the falling weight to restrict flow through the outlet passage, said means being adapted to restrict the flow beginning at the warning position, whereby the signal will move relatively rapidly from the "Go" position to the warning 50 position and thereafter move relatively slowly to the "Stop" position.

55. 7. A signal having, in combination: a signal member movable between two positions; a signal weight movable from a lower position to an upper position and vice versa, said signal weight being operatively connected to the signal member 60 whereby the upward movement of the signal weight will move the signal to one position and the reverse gravitation of the signal weight will move the signal to the alternate position; a latch means to releasably hold the signal weight 65 at the raised position, said latch means being adapted to release the signal weight in response to the approach of a control vehicle; an hydraulic lift for elevating the signal weight; power means to pump fluid into said hydraulic lift, thereby elevating the signal weight to the latched 70 position, said hydraulic lift having an outlet passage for the release of said fluid under pressure from the falling weight; and an apertured plunger movable by the falling weight into said 75

outlet passage against the fluid stream to retard the fall of the weight.

8. A signal having, in combination: a signal member movable between two positions; a signal weight movable from a lower position to an upper 5 position and vice versa, said signal weight being operatively connected to the signal member whereby the upward movement of the signal weight will move the signal to one position and the reverse gravitation of the signal weight will 10 move the signal to the alternate position; a latch means to releasably hold the signal weight at the raised position, said latch means being adapted to release the signal weight in response to the approach of a control vehicle; an hydraulic cylinder; 15 a piston in said cylinder operatively connected with the signal weight; a power driven pump to deliver fluid to the cylinder under the piston, thereby elevating the weight; and control means to stop the pump when the weight reaches its 20 elevated position, said control means including an auxiliary hydraulic means having its inlet connected to the cylinder adjacent the desired upper position of the piston, whereby said auxiliary means is energized by fluid pressure when 25 the piston clears said inlet.

9. A signal having, in combination: a signal mechanism adapted to gravitate from a first signal position to a second signal position; a latch 30 to releasably hold said mechanism at the first position; a latch weight; an electro-magnet adapted to hold the latch weight elevated, said weight being adapted to open the latch by impact when released by the electro-magnet; an electric circuit normally energizing said electro- 35 magnet, said circuit being adapted to be interrupted by an approaching control vehicle to release the latch weight; power driven hydraulic means to move the signal mechanism against gravity from the second signal position to the first signal 40 position for engagement with said latch; and auxiliary hydraulic means adapted to receive fluid under pressure from the first hydraulic means for the purpose of restoring the latch weight to 45 magnetic engagement with the electro-magnet at the latched position of the mechanism.

10. A signal having, in combination: a signal mechanism adapted to gravitate from a first signal position to a second signal position; a latch 50 to releasably hold said mechanism at the first position; a latch weight; an electro-magnet adapted to hold the latch weight elevated, said weight being adapted to open the latch by impact when released by the electro-magnet; an electric circuit normally energizing said electro-magnet, 55 said circuit being adapted to be interrupted by an approaching control vehicle to release the latch weight; electrically driven hydraulic means to move the signal mechanism against gravity from the second signal position to the first signal position for engagement with said latch; an electric circuit to energize said hydraulic means; two electric switches associated with the second circuit arranged to cause the circuit to be energized when both switches are closed, the first of said 60 switches being normally closed and being adapted to open temporarily in response to the approaching control vehicle, the second switch having an inherent tendency to close; means associated with said second switch and the electro-magnet 65 whereby the electro-magnet when energized holds said second switch open; and auxiliary hydraulic means adapted to receive fluid under pressure from the first hydraulic means for the purpose of restoring the latch weight to magnetic engage- 70 75

ment with the electro-magnet at the latched position of the mechanism, and for the further purpose of opening said second switch when the signal mechanism reaches the latched position.

5 11. A signal having, in combination: a signal mechanism adapted to gravitate from a first signal position to a second signal position; a latch to releasably hold said mechanism at the first position; a latch weight; an electro-magnet adapted to hold the latch weight elevated, said weight being adapted to open the latch by impact when released by the electro-magnet; an electric circuit normally energizing said electro-magnet, said circuit being adapted to be interrupted by 10 an approaching control vehicle to release the latch weight; electrically driven hydraulic means to move the signal mechanism against gravity from the second signal position to the first signal position for engagement with said latch; an electric circuit to energize said hydraulic means; two electric switches associated with the second circuit arranged to cause the circuit to be energized when both switches are closed, the first of said switches being normally closed and being adapted 15 to open temporarily in response to the approaching control vehicle, the second switch having an inherent tendency to close; means to hold said second switch open while the signal mechanism is in the first position; auxiliary hydraulic means 20 adapted to receive fluid under pressure from the first hydraulic means for the purpose of restoring the latch weight to magnetic engagement with the electro-magnet at the latched position of the mechanism; and means restricting flow of fluid 25 from the first hydraulic means under pressure

from the gravitating mechanism, thereby controlling movement of the mechanism from the first signal position to the second signal position.

12. A signal having, in combination: a signal member mounted to rotate between two positions; a signal weight movable from a lower position to an upper position, and vice versa, said signal weight being operatively connected to the signal member whereby non-rotary upward movement of the signal weight will rotate the signal 10 to one position and reverse non-rotary gravitation of the signal weight will move the signal to the alternate position; guide means to prevent rotation of the weight; an electrical latch means adapted when energized to releasably hold the signal weight at the raised position; an electric circuit normally energizing the latch means, said circuit being adapted to be interrupted by an approaching control vehicle, thereby de-energizing the latch to release the signal weight; and 20 power means adapted to be energized upon the departure of the control vehicle to lift the signal weight back to its normal latched position.

13. In a signal of the class described, a yielding connection between a vertical shaft and a horizontally pivoted signal member, said connection comprising: a base mounted on the vertical shaft, said base presenting on its upper surface a plurality of radially disposed V-shaped valleys; and a complementary member rotatably mounted on 25 said base co-axial thereto, said member supporting the signal member and normally resting in the vertices of said valleys at all positions of the signal member.
